[57] **CLAIM**

The ornamental design for a recumbent tricycle body, as shown and described.

DESCRIPTION

FIG. 1 is a perspective view of a recumbent tricycle body showing our new design and in which the wheels and sprocket chain are shown in broken lines for illustrative purposes only;

FIG. 2 is a top plan view thereof;

FIG. 3 is a bottom plan view thereof;

FIG. 4 is a right-side elevational view thereof;

FIG. 5 is a left-side elevational view thereof;

FIG. 6 is a front elevational view thereof; and

FIG. 7 is a rear elevational view thereof.
